UNITED STATES PATENT OFFICE.

GEORGE NICHOLAS EINSELE, OF CEDAR LAKE, INDIANA.

STRING-TRUING MACHINE.

Application filed May 1, 1926. Serial No. 106,121.

This invention relates to string-truing machines and relates particularly to string-truing machines adapted to grind or cut a plurality of strings of various diameters, reducing each string an equal amount, and producing a uniform thickness throughout its length.

Strings for musical instruments and the like are commonly manufactured from guts, and in their raw condition these guts are rough and irregular and of varying thickness throughout their length. In order to obtain the best results from a stringed instrument, so far as tonal qualities are concerned, the strings must be smooth and uniform in diameter, or true. Also, since these strings are of various lengths ranging from 36 inches to over eight feet, depending upon the instrument in which they are to be used, the machine is adapted to be adjustable to any desired length of string.

One of the objects of this invention is to provide a string-truing machine in which a plurality of strings of varying diameter may be ground simultaneously.

Another object of this invention is to provide an improved automatically controlled string-truing machine.

A further object of this invention is to provide a string-truing machine in which strings of various lengths may be trued.

A further object is to provide a string-truing machine which will turn out work rapidly.

A further object is to provide a string-truing machine which will be durable and efficient.

Further objects and advantages will be apparent from the drawing when read in connection with the following description, in which drawings:

Figure 1 is a top plan view of the string-truing machine in which parts have been broken away;

Fig. 2 is a side elevational view of Fig. 1;

Fig. 3 is an enlarged top plan view of the carriage structure;

Fig. 4 is a section on the line 4—4 of Fig. 3;

Fig. 5 is a section on the line 5—5 of Fig. 3;

Fig. 6 is a section on the line 6—6 of Fig. 3; and

Fig. 7 is a top plan section on the line 7—7 of Fig. 4.

Referring to the drawings, and particularly to Figs. 1 and 2 thereof, a supporting structure 10 is shown having an adjustable headstock 11 and an adjustable tailstock 12 mounted thereon. A plurality of revolving centers, or arbors, 13 and 14 are mounted in the headstock 11 and the tailstock 12 respectively between which centers are suspended strings 15. Journalled in said head and tailstocks, and extending the full length of the machine to an end support 16, are a pair of tracks 17 preferably formed of piping, and upon said tracks a carriage 18 is mounted between the head and tailstocks. This carriage carries cutting elements, having abrading surfaces, and moves longitudinally in a reciprocating manner along the tracks 17. A cross-head structure 19 is mounted on one end of the tracks 17 and is connected to the carriage by means of the rods 20.

Movement is imparted to the cross-head 19 by means of a connecting rod 21 fastened thereto and extending to a fly-wheel 22, which latter is mounted on a shaft 22^a in bearings 23 on the supporting structure 10. The fly-wheel is connected to a suitable source of power by means of a belt 24. The driving means just described provide a smooth and somewhat cushioned travel of the carriage, inasmuch as the rate of speed of the carriage gradually increases and decreases at the beginning and toward the end respectively of the travel of the carriage in either direction.

Also, the cut to be taken on the string by the abrading surfaces is so small, perhaps 1/1000 of an inch, that were the connecting rod 21 directly connected to the carriage, any tendency to bind or tilt the carriage, such as at the beginning of the stroke, might result in an uneven cut and, therefore, be detrimental to the effect of the machine on the strings. Therefore, it is the best practice to have the connecting rod indirectly associated with the carriage by means of the cross-head 19 and the tie-rods 20, as hereinbefore described.

The tailstock 12 comprises a U-shaped structure secured to the supporting structure 10 by means of bolts 25 projecting through slots 26. A pair of projections 27, preferably formed integral with the tailstock, also project through slots 26 and carry a pair of racks 28 suitably mounted thereon for en-

gagement with pinions 29 mounted on a shaft 30.

The headstock 11 comprises a U-shaped structure secured to the supporting structure 5 by means of bolts 31 projecting through slots 32. A pair of projections 33, preferably formed integral with the headstock, also project through slots 32 and carry a pair of racks 34 suitably mounted thereon for engagement with pinions 29.

Upon loosening the bolts 25 and 31, a rotation of the pinions 29 by means of a crank 35 will move the head and tailstocks to a closer relation, or, move them farther apart. By 15 this means, the varying lengths of strings may be accommodated without the necessity of an undue amount of mechanical skill. In order that the travel of the carriage may be increased or decreased, and care for this variation in the length of the strings, a slot 36 is provided in the fly-wheel 22, which slot is disposed radially from a point near the center, and to said slot the connecting rod 21 is connected by means of bolt 37. It is obvious 25 that by moving the connection thus made a greater distance from the center, a greater travel of the carriage is effected and vice versa.

When it is necessary to accommodate a 30 string of different length than that length for which the machine is set, the bolts 25 and 31 are loosened and the crank 35 is turned in the proper direction to move the head and tailstocks an equal distance in opposite directions, from or toward a central point. It will be apparent that inasmuch as shaft 22^a, upon which the fly-wheel 22 is mounted, is fixedly mounted on the supporting structure 10, a central point is definitely established. 35 A movement of the connection between the connecting rod 21 and the fly-wheel 22 away from or toward the center of the fly-wheel will increase or decrease the length of travel of the carriage an equal distance on each side 40 of the central point established by the shaft 22^a. The two aforementioned central points are so related as to permit of the varying of the distance between the head and tailstocks and the varying of the distance of travel of 45 the carriage in harmony with each other.

The revolving centers or arbors 14 of the tailstock 12 comprise a plurality of spindles journaled in the U-shaped structure between the supporting arms thereof, each spindle 55 having a gear 38 in engagement with the gear of the adjacent spindle, and a hook 39 to which one end of the string 15 is fastened. The revolving centers 13 of the headstock 11 comprise a plurality of spindles having gears 60 secured thereto in engagement with the gear of the adjacent spindle and journaled in said headstock between the supporting arms thereof. Each spindle has a rod 41 journaled therein and slidable longitudinally 65 thereof with a keyway 42 engaging a suitable

key projecting from said spindle in order to receive rotation from the gears 40. A hook 43 is formed on the end of the rod 41 for receiving the other end of string 15.

One end of the string 15 is fastened to the hook-member 39 and the other end of said string is similarly fastened to the hook-member 43. The string is then held in a taut relation by means of a weight 44 fastened to a bearing member 45 by means of a cord or wire 46. As the bearing member 45 is secured to the longitudinally slidable rod 41, the weight 44 will tend to stretch the strings 15 between their respective hooks and hold them in a proper relation for the operation 75 of the carriage 18.

These revolving centers 13 and 14 receive their rotation from gears 47 and 48 respectively, which gears are secured to a shaft 49 suitably connected to a motor 50. They are revolved at a speed of approximately eight hundred revolutions per minute, while the travel of the carriage is approximately sixty 80 strokes per minute. It is obvious that the great difference in the rate of speed of the travel of the carriage and the rotation of the string will produce a true circular cross-section of the string.

Referring now more particularly to Figs. 3 and 7, the carriage 18 comprises a lower rectangular supporting structure 51 in which is slidably mounted a lower rectangular frame member 52. An upper rectangular frame member 53 is hinged at one end thereof to the lower frame member 52 by means of a bracket 54 secured to the upper frame member 53, a pair of brackets 55 secured to projections 56 which extend from the lower frame member 52 and a rod 57 projecting through brackets 54 and 55. Bracket 54 is provided with elongated slots 58, in order to permit of a horizontal positioning of the upper frame member regardless of the amount of separation between the upper and lower frame members.

The supporting structure 51 comprises a rectangular frame with recesses 60 on two opposite sides thereof and preferably has a plurality of cross-members 59 secured thereto by means of screws 61 which contain a plurality of recesses 62, and in each recess a coil spring 63 is positioned.

The lower frame member 52 comprises a rectangular frame having projections 64 adapted to engage the recesses 60 for slidable engagement therewith and contain a plurality of lower blocks 65 yieldingly held in position by means of coil springs 63. This frame member 52 is rabbeted so as to provide depressions 66 into which the projections of flanges 67 of the blocks 65 enter. In order to afford satisfactory bearing surface, each of the projections 67 are provided with two pointed pins 68 which rest against the surfaces of the depressions, whereby, should any 125

foreign matter collect in said depressions, the positioning of the blocks would not be affected.

The upper frame member 53 comprises a frame member adapted to receive a plurality of upper blocks 69 and has a recess 70 on its opposite sides to receive projections 71 of the blocks 69. The only function of the recesses and the projections thus provided is to prevent the blocks from falling through the opening, and this construction does not, therefore, limit the travel of the blocks in any other manner. In order to prevent the blocks from falling out when the frame member is in a tilted-back-position, a pair of overlapping metal strips 72 are provided and secured to the frame member 53 by means of screws 73. Slots 74 are provided in the strips 72 and disposed angularly therein so that, should it be necessary to remove a block, the screws 73 are loosened and the strips pulled back thus shifting the overlapping portion clear of the projections 71.

The blocks 69 are located directly above the blocks 65 and have their lower surface coated with a suitable abrading material, as indicated at 75. The ends of the lower block may, or may not, be coated with an abrading material, but both ends thereof are slightly tapered. Between the surfaces of the aforementioned two blocks, the strings are located, and, in operation, are rotated rapidly therebetween, while the entire carriage is traveling in a reciprocating manner over the full length of the string.

An automatically actuated means is provided for lowering the upper set of abrading blocks in order that an additional cut will be removed from the revolving strings on the return travel of the carriage. For lowering the abrading or upper blocks 69, the upper frame member 53 is provided with inclined lower surfaces 76 and rests on the upper ends of three vertical pins 77. A slight movement to the right in the direction of the incline would cause a slight lowering of the blocks 69 and thereby produce a deeper cut on the strings. It is preferable to provide a three-point support, in order to provide for an exact cut, since any irregularities, such as the warping of the frame, would be harmful to the operation of the machine were other supporting means used.

The means for automatically causing the shift of the upper frame member to produce the deeper cut, as aforesaid, comprises a bell-crank lever 78 pivotally mounted on a bracket 79 and secured to the upper frame member. On the return travel of the carriage, one end of the bell-crank lever 78 is caused to abut an adjustable screw 80 while the carriage continues to travel. As the other end of the bell-crank lever has a pin and slot connection with an arm 81 which in turn is provided with a pawl portion in engagement with a ratchet

wheel 82, a further travel beyond the point at which the bell-crank lever abuts the adjustable screw 80, will cause a movement of the arm 81 and produce a partial rotation of the ratchet wheel 82.

A frame 83 is secured to the upper frame member 53 and has a threaded shaft 84 screwed therein. The ratchet wheel 82 is mounted on shaft 84 between the arms of a forked projection 85 and is held in an impulsive driving relation with respect to said shaft by means of a spring washer 86 pressing said gear against the shoulder 87. As the gear 82 and the threaded shaft 84 are rotated, the shaft is held from endwise travel by means of the forked projection and, therefore, the frame 83 causes the upper frame member 53 to move in one direction or the other. An adjustable stop 88 is secured to a projection 89 on the lower frame member 52 to regulate the distance of the travel of the upper frame member. This regulation is permitted by means of the slip connection provided by the spring washer 86. As the upper frame member 53 abuts the adjustable stop 88, the gear 82 is allowed to slip on the shaft 84 and further movement is stopped.

The upper abrading blocks 69 are so constructed as to prevent a tilting of the blocks. For this purpose an arm 90 is provided on each block, and at the upper end of said arm a pin 91 extends through to the exact width of the block. A set screw 92 is provided on a supporting structure 93 in approximate alignment with the pins 91. A screw 94, having a hand wheel 95, is provided on the opposite side of the set screw 92 and is journalled in the supporting structure 93 at a point near the lower end of the projecting arms 90. Each of the blocks 69 is provided with an arcuate surface on one side thereof and a straight side on the opposite side, each adjacent block having its arcuate side abutting the straight side of the other. This acts as a preventative against any foreign substance misaligning the blocks in addition to providing a more efficient bearing surface. The hand wheel 95 is tightened so that the screw 94 presses against the first block which action is carried through the blocks and against the set screw 92. The blocks are thus held in any desirable position, and as shown clearly in Fig. 6 of the drawings, the diameters of the strings may be of any size.

In order not to cut a groove in the abrading surface and to get the use of the full width thereof, the lower frame member 52 is movable in the recesses 60 provided in the supporting structure 51. This movement is effected by a screw member 96 having a screw threaded engagement with the structure 51 and having a swivel connection with the lower frame member 52. This may be operated manually or automatically. The automatic means provided for in this instance

comprise two ratchet wheels 97 and 98 mounted on the screw member 96 and having their teeth cut in different directions, as shown more particularly in Fig. 5 of the drawings. 5 A duplex pawl 99 is pivotally mounted on the upper frame member 53 and is provided with hook members 100 and 101, each of the latter lying in the plane of its respective ratchet member 97 or 98. Upon the lifting 10 of the upper frame member 53, the hook 101 engages a tooth of the ratchet 98 and rotates the screw 96 in one direction to move the frame members 52 and 53 in order that a fresh surface be provided for the string 15. Similarly, if the pawl 99 is pivoted to a position 15 on the reverse side of the ratchet members, the hook 100 engages a tooth of the ratchet 97 and rotates the screw 96 in the opposite direction. A pin 102 is provided to hold the 20 pawl in an off-center position in either instance, in order that the pawl will be forced outwardly by the ratchet wheels when the upper frame member is assuming its normal position on the strings. This is, of course, 25 but one of several means that may be provided for by automatically adjusting the abrading surfaces so that the full width thereof may be utilized and this invention is not, therefore, to be limited to this means solely.

30 In the operation of the machine, a plurality of strings are suspended between the revolving centers 13 and 14. The carriage, carrying a plurality of pairs of yieldingly mounted abrading blocks, between which the 35 strings are rapidly rotated, is moved along this track in a reciprocating manner and longitudinally of the strings. On the return travel of the carriage, the distance between the abrading blocks is slightly reduced and 40 a new cut is made on the strings. This operation is continued until the upper frame member abuts the stop 88 which predetermines the amount of cut to be taken on the 45 strings. The upper frame member is then lifted clear of the strings and the strings are removed and a new supply of strings placed between the centers.

50 In supplying a fresh supply of strings to the machine, the hand wheel 95 is loosened and the blocks 69 are allowed to rest on the strings independently of each other, and, as shown in Fig. 6, various diameters of strings 55 may be accommodated. The hand wheel 95 is then tightened and the machine is ready for operation. It is obvious that the same amount of cut will be taken from each string and that any irregularities in the diameter of the string will be remedied. If, however, any undue pressure is created, the coil springs 60 will permit the lower blocks 65 to yield and thereby relieve the pressure.

65 Two sets of notched flanges 103 are provided. One set is fixed to each side of the supporting structure for steadyng the strings at points near the abrading surfaces, while

the strings are placed in these notches respectively and steadied therein as they revolve. In order to adjust the width of the notch, each set of flanges comprises two members, the outer member being shiftable to vary the 70 effective width of the notch in the adjacent flange.

As a result of this invention, it is possible to simultaneously true a plurality of strings having various diameters; it is also possible 75 to adjust the travel of the carriage and the means for suspending the strings to accommodate the various lengths demanded by the different instruments; it is possible to turn out the work rapidly and accurately, and, finally, the device is automatically operated 80 which permits of its being operated by unskilled labor thereby reducing the cost of the resultant product to a minimum.

While a single embodiment of this invention is herein shown and described, it is to be understood that this invention is not to be limited to that specific structure, since many modifications may be apparent to those skilled in the art without departing from the 90 spirit of the invention, and I desire, therefore, that the same be limited only by the scope of the appended claims and the prior art.

I claim:

1. A string truing machine comprising 95 means for rotating a string about an axis extending longitudinally of the string, a non-rotatable cutting element for engaging said string during rotation thereof, means for effecting relative movement between said string and cutting element in a direction longitudinally of the string, and yieldable supporting means opposite said cutting element for holding said string against said cutting element. 100

2. A string truing machine comprising 105 means for rotating a string about an axis extending longitudinally of the string, a non-rotatable cutting element for engaging said string during rotation thereof, means for effecting relative movement between said string and cutting element in a direction longitudinally of the string, supporting means 110 opposite said cutting element for holding said string against said cutting element, and means for holding said supporting means a predetermined distance from said cutting element as the string is rotated to determine the depth of cut. 115

3. A string truing machine comprising 120 means for rotating a string about an axis extending longitudinally of the string, a non-rotatable cutting element for engaging said string during rotation thereof, means for effecting relative movement between said string and cutting element in a direction longitudinally of the string, supporting means 125 opposite said cutting element for holding said string against said cutting element, and means for yieldingly holding said sup- 130

- porting means a pre-determined distance from said cutting element as the string is rotated to determine the depth of cut.
4. A string truing machine comprising means for holding a plurality of strings substantially parallel to each other, and rotating them about their axes, cutting means for engaging said strings during rotation thereof, and means for effecting relative movement between said strings and said cutting means in a direction longitudinally of the strings, said cutting means comprising a plurality of adjustable cutting elements, one for each string.
5. A string truing machine comprising means for holding a plurality of strings substantially parallel to each other, and rotating them about their axes, cutting means for engaging said strings during rotation thereof, and means for effecting relative movement between said strings and said cutting means in a direction longitudinally of the strings, said cutting means comprising a plurality of cutting elements, one for each string, and supporting means comprising a plurality of supports, one for each cutting element for holding said strings against said cutting elements.
6. A string truing machine comprising means for holding a plurality of strings substantially parallel to each other, and rotating them about their axes, cutting means for engaging said strings during rotation thereof, and means for effecting relative movement between said strings and said cutting means in a direction longitudinally of the strings, said cutting means comprising a plurality of cutting elements, one for each string, and said supporting means comprising a plurality of supports, one for each cutting element for holding said strings against said cutting elements, each cutting element and its support being relatively adjustable, independently of the others, to enable strings of different thicknesses to be simultaneously operated on.
7. A string truing machine comprising means for holding a plurality of strings substantially parallel to each other, and rotating them about their axes, cutting means for engaging said strings during rotation thereof, and means for effecting relative movement between said strings and said cutting means in a direction longitudinally of the strings, said cutting means comprising a plurality of cutting elements and means whereby said cutting elements may be adjusted independently to operate on strings of different thicknesses, and may be adjusted collectively with respect to the strings in adjusting for a cut.
8. A string truing machine comprising means for holding a plurality of strings substantially parallel to each other, and rotating them about their axes, cutting means for engaging said strings during rotation thereof, and means for effecting relative movement between said strings and said cutting means in a direction longitudinally of the strings, said cutting means comprising a plurality of cutting elements and a holder in which said cutting elements are independently adjustable for operation on strings of different thicknesses, said holding means being provided with means for clamping the cutting elements in their adjusted positions.
9. A string truing machine comprising means for holding a plurality of strings substantially parallel to each other, and rotating them about their axes, cutting means for engaging said strings during rotation thereof, and means for effecting relative movement between said strings and said cutting means in a direction longitudinally of the strings, said cutting means comprising a plurality of cutting elements and a holder in which said cutting elements are independently adjustable for operation on strings of different thicknesses, said holder being adjustable with respect to the strings in adjusting for a cut.
10. A string truing machine comprising means for holding a plurality of strings substantially parallel to each other, and rotating them about their axes, cutting means for engaging said strings during rotation thereof, and means for effecting relative movement between said strings and said cutting means in a direction longitudinally of the strings, said cutting means comprising a plurality of elongated non-rotatable cutting elements, one for each string, extending longitudinally of the strings.
11. A string truing machine comprising means for holding a plurality of strings substantially parallel to each other, and rotating them about their axes, cutting means for engaging said strings during rotation thereof, and means for effecting relative movement between said strings and said cutting means in a direction longitudinally of the strings, said cutting means comprising a plurality of cutting elements and a holder in which said cutting elements are independently adjustable for operation on strings of different thicknesses, said holding means being provided with means for clamping the cutting elements in their adjusted positions.
12. A string truing machine comprising means for holding a plurality of strings substantially parallel to each other, and rotating them about their axes, cutting means for engaging said strings during rotation thereof, and means for effecting relative movement between said strings and said cutting means in a direction longitudinally of the strings, said cutting means comprising a plurality of cutting elements and a holder in which said cutting elements are independently adjustable for operation on strings of different thicknesses, said holding means being provided with means for clamping the cutting elements in their adjusted positions, said holder being adjustable with respect to said

strings to adjust the cutting elements collectively with respect to the strings in adjusting for a cut.

13. A string truing machine comprising means for holding a plurality of strings substantially parallel to each other, and rotating them about their axes, cutting means for engaging said strings during rotation thereof, and means for effecting relative movement between said strings and said cutting means in a direction longitudinally of the strings, said cutting means comprising a plurality of cutting elements and a holder in which said cutting elements are independently adjustable for operation on strings of different thicknesses, said holding means being provided with means for clamping the cutting elements in their adjusted positions, said cutting elements having line contacts with each other when clamped together.

14. A string truing machine comprising means for rotating a string about an axis extending longitudinally of the string, a non-rotatable cutting element for engaging said string during rotation thereof, means for effecting relative movement between said string and cutting element in a direction longitudinally of the string, supporting means opposite said cutting element for holding said string against said cutting element, and means for automatically varying the distance between said cutting element and supporting means in adjusting for a cut.

15. A string truing machine comprising means for rotating a string about an axis extending longitudinally of the string, a cutting element for engaging said string during rotation thereof, means for effecting relative movement between said string and cutting element in a direction longitudinally of the string, supporting means opposite said cutting element for holding said string against said cutting element, and means controlled automatically by the relative longitudinal movement between the string and cutting element for varying the distance between the cutting element and supporting means in adjusting for a cut.

16. A string truing machine comprising means for rotating a string about an axis extending longitudinally of the string, a cutting element for engaging said string during rotation thereof, means for effecting relative movement between said string and cutting element in a direction longitudinally of the string, supporting means opposite said cutting element for holding said string against said cutting element, and means for varying the distance between said cutting element and supporting means in adjusting for a cut, comprising a member having a surface inclined with respect to said string, a member engaging said surface, and means for effecting relative movement between said members.

17. A string truing machine comprising

means for rotating a string about an axis extending longitudinally of the string, a cutting element for engaging said string during rotation thereof, means for effecting relative movement between said string and cutting element in a direction longitudinally of the string, supporting means opposite said cutting element for holding said string against said cutting element, and means for varying the distance between said cutting element and supporting means in adjusting for a cut, comprising a member having a surface inclined with respect to said string, a member engaging said surface, and means for effecting relative movement between said members, said last means comprising a screw and ratchet mechanism for operating said screw controlled automatically by the relative longitudinal movement between said cutting element and string.

18. A string truing machine comprising means for rotating a string about an axis extending longitudinally of the string, a cutting element for engaging said string during rotation thereof, means for effecting relative movement between said string and cutting element in a direction longitudinally of the string, supporting means opposite said cutting element for holding said string against said cutting element, and means for automatically varying the distance between said cutting element and supporting means in adjusting for a cut, comprising a screw and ratchet mechanism for operating said screw controlled by the relative longitudinal movement between said cutting element and string.

19. A string truing machine comprising means for rotating a string about an axis extending longitudinally of the string, a cutting element for engaging said string during rotation thereof, means for effecting relative movement between said string and cutting element in a direction longitudinally of the string, supporting means opposite said cutting element for holding said string against said cutting element, and means for automatically varying the distance between said cutting element and supporting means in adjusting for a cut, comprising a ratchet mechanism controlled by the relative longitudinal movement between said cutting element and string.

20. A string truing machine comprising means for rotating a string about an axis extending longitudinally of the string, a cutting element for engaging said string during rotation thereof, means for effecting relative movement between said string and cutting element in a direction longitudinally of the string, and means for adjusting said cutting element laterally of the string in order to utilize the entire cutting surface of said cutting element, a holder on which said cutting element is mounted for movement to-

ward and from the string, and means controlled by movement of said holder for effecting the lateral adjustment of the cutting element.

5 21. A string truing machine comprising means for rotating a string about an axis extending longitudinally of the string, a cutting element for engaging said string during rotation thereof, means for effecting relative movement between said string and cutting element in a direction longitudinally of the string, supporting means opposite said cutting element for holding said string against

said cutting element, and means for varying the distance between said cutting element and supporting means in adjusting for a cut, comprising a member having a surface inclined with respect to said string, a three-point support for engaging said surface, and means for effecting relative movement between said member and said three-point support.

In witness whereof, I have hereunto subscribed my name.

GEORGE NICHOLAS EINSELE.
